UNITED STATES PATENT OFFICE.

WILHELM OELSCHLÄGEL, OF NEW YORK, N. Y.

ICE-SKATE.

1,218,451.

Specification of Letters Patent.

Patented Mar. 6, 1917.

Application filed November 29, 1915. Serial No. 64,112.

To all whom it may concern:

Be it known that I, WILHELM OELSCHLÄGEL, a subject of the Emperor of Germany, residing at New York, in the county of New York and State of New York, have invented certain new and useful Improvements in Ice-Skates; and I do hereby declare the following to be a full, clear, and exact description of the invention, such as will enable others skilled in the art to which it appertains to make and use the same.

This invention relates to skates and more particularly to ice skates for racing and fancy skating.

It has for an object to provide an ice skate having certain features of construction to permit a more perfect balance of the skater and the runner of said skate is specifically curved for a portion of its length to more conveniently dispose the center of gravity to the skater to permit acceleration and also to permit the use of said skate for demonstration work.

A further object of this invention is the provision of a skate for attachment to a shoe in which said skate is more rigidly supported by said shoe to form a positive grip of said skate upon said shoe so that a wearer may have more perfect control when skating.

A further object of this invention is to provide an ice skate which is rigidly attached to a shoe whereby the toe, ball and heel of the shoe are rigidly connected to the skate so that no flexibility of support between the toe and ball of the shoe and skate are had, but between the ball and heel of the shoe, the desired flexibility may be had to compensate for any resiliency in the runner of the skate under the instep.

A further object of this invention is a provision of a stop formed on the skate near the forward end to assist the three points of support of said skate to a shoe.

A further object of this invention is the provision of a skate having a portion of the runner straight about the central portion of said runner and to have the forward end of said runner in advance of said straight portion decidedly curved to cause said straight portion to form a tangent to said curved portion and to have the point of tangency occur substantially under the ball of the foot of the wearer.

A further object of this invention is to provide a skate for attachment to a shoe to

have the sole of the shoe relatively parallel with the skating surface and to have said skate connected to the sole of the shoe at three points therealong to establish a most rigid connection where desired and to permit flexibility of connection to compensate for the flexing of the runner.

Further objects will be apparent from the following specification, appended claim and drawings, in which—

Figure 1 is a side elevation of a shoe showing the skate attached thereto,

Fig. 2 is a bottom view of the skate and shoe,

Fig. 3 is a cross sectional view of the runner as on the line 3—3 of Fig. 1, and

Fig. 4 is a cross sectional view as on the line 4—4 of Fig. 1.

This skate is designed for ordinary usage but more especially for fancy skating and in view of the certain requirements for special features of construction necessary for fancy skating, the following specification and drawings will show wherein the general lines of this skate are a departure from the present type of skate.

Referring to the drawings, 10 indicates the shoe having the sole 11 and heel 12 formed thereon as usual. A skate comprising the runner 13 and the standards 14 and 15 is attached to the sole and heel of said shoe in having wings 16 formed on the standard 14, screwed or otherwise attached to the heel as at 17 and in having the enlarged wings 18 formed on the standard 15 which are also attached as by the screws 19 or otherwise if so desired. The wings 16 substantially support all parts of the heel 12 and the wings 18 are enlarged to substantially support the ball of the sole of the shoe. It is seen that the wings 16 and 18 to one side of the runner 13 are larger than on the opposite side and that when said skate is applied to the shoe, the runner is offset from the straight line along the sole of the shoe to cause said runner to underlie the ball of the foot toward the large toe. In offsetting the runner from a true center line along the bottom of the shoe, it is seen that a better balance of the skate is had and that the runner underlies the toes of the foot having the greatest strength.

The forward end of the runner 13 is bent upon itself as at 20 and terminates in the wings 21 which are also secured to the

underface of the toe of the sole as by screws 22 or otherwise if desired, and rising from said runner in advance of the wings 21 are the stops 23 against which the sole 11 bears. 5 It is seen that in this skate, attachment to the shoe is provided at three points along the sole of the shoe and that the wings 18 and 21 are of such proportions as to properly reinforce the sole of the shoe so that 10 when the skate is attached to the shoe, the sole 11 is rigidly held in the major portion of its area to the skate and in view thereof, the forward part of the skate must move with the foot in a positive manner without 15 any deflections incident to the yielding of the shoe.

The runner 13 is of slightly reduced cross sectional area between the standards 14 and 15 as shown in Fig. 3 of the drawing to 20 render said portion of the runner resilient and said runner is hollow ground in the usual manner from the heel to the point indicated at 24 from where the face of said runner is plane up to the series of serrations 25 25. This serrated portion is formed on the forward end of the skate to form the desired checking effect of the momentum of the skater when desired, and the serrations are in staggered relation as shown. The 30 foremost serration on the skate affords a tip or point upon which the skater may swing as a pivot. The runner 13 has a central portion thereof in a straight line between the points 26 and 27 from where the 35 runner curves upwardly to the heel 28. From the point 26 to the forward end of the skate, the runner has a decided turn upwardly and the point 26 is the point of tangency between the straight portion and 40 the upward turned portion. This point of tangency is disposed substantially under the ball of the foot of a wearer and when skating, the body of the wearer pitches forward to such a degree as to utilize that part of 45 the runner between the numerals 24 and 26 in certain forms of skating and in the accel-

eration of speed or in starting from a position at rest.

It will be understood by those familiar with fancy skating that the several distinct 50 features set forth in this application contribute toward the accomplishment of graceful and fancy skating and slight modifications in the several characteristic features may be made without departing from the 55 scope of the appended claim.

Having thus described my invention, I claim:—

In an ice skate of the class described, a runner having the forward and rear ends 60 curved slightly upwardly from a straight section, said runner being hollow ground for a major portion of its length, from the heel to near the toe, the forward end of said runner rising above the general line of said runner where it terminates in a plate forming wings to the opposite sides of said runner, a stop formed of said upturned end in advance of said plates, to contact with the forward end of the sole of a shoe supporting 65 said skate, a standard rising from said runner under the ball of the foot of a wearer, said standard having wings formed thereon which extend from the sides of said standard, a second standard formed on said 70 runner under the heel of a foot having wings formed thereon, fastening means passing through the several wings formed on said standards and the upturned end of the runner, and said runner having a reduced 75 cross sectional dimension between the standards under the ball and heel of a foot to permit that portion of the runner so reduced in its cross sectional dimension to be relatively flexible.

In testimony whereof I affix my signature in presence of two witnesses.

WILHELM OELSCHLÄGEL.
